(57) **CLAIM**
I claim the ornamental design for a female QD sling swivel, as shown and described.

DESCRIPTION

FIG. 1 is a front perspective view of a female QD sling swivel, showing my new design;

FIG. 2 is a top plan view thereof, the bottom plan view being a mirror image thereof;

FIG. 3 is a left-side elevational view thereof, the right-side elevational view being a mirror image thereof;

FIG. 4 is a rear elevational view thereof;

FIG. 5 is a front elevational view thereof; and,

FIG. 6 is a cross-sectional view thereof, taken along line 6-6 of FIG. 5.
